UNITED STATES PATENT OFFICE.

OBED CHARLES HAWKES, OF BIRMINGHAM, COUNTY OF WARWICK,
ENGLAND.

DESIGN FOR BEVELED GLASS.

SPECIFICATION forming part of Design No. 18,510, dated August 7, 1888.

Application filed July 11, 1888. Serial No. 279,667. Term of patent 14 years.

To all whom it may concern:

Be it known that I, OBED CHARLES HAWKES, a subject of the Queen of Great Britain, residing at Birmingham, in the county of Warwick, 5 England, have invented and produced a new and original Design for Beveled Glass, of which the following is a specification, reference being had to the accompanying drawings, forming part thereof.

10 The leading feature of my design for beveled glass is an ogee border within the bevel thereof.

Figure 1 represents a section of a piece of beveled glass embodying my invention. Fig. 15 2 represents a face view thereof.

In the drawings, A represents a piece of glass having on its face a beveled rim, a, and an ogee border, b, within said rim.

I claim—

A design for beveled glass having on its 20 face a beveled rim, and an ogee border within said rim, substantially as shown and described.

OBED CHARLES HAWKES.
